UNITED STATES PATENT OFFICE.

HARTLAND LAW AND HERBERT E. LAW, OF SAN FRANCISCO, CALIFORNIA.

BATH-GOWN.

SPECIFICATION forming part of Letters Patent No. 601,835, dated April 5, 1898.

Application filed August 4, 1897. Serial No. 647,078. (No model.)

To all whom it may concern:

Be it known that we, HARTLAND LAW and HERBERT E. LAW, citizens of the United States, residing at San Francisco, in the county 5 of San Francisco, State of California, have invented certain new and useful Improvements in Bath-Gowns, of which the following is a specification, reference being had therein to the accompanying drawings.

- 10 This invention relates to gowns for baths, and more particularly to a gown within which the bather may be completely inclosed for the purpose of retaining within the gown the heated air or vapor used in the bath.
- 15 The invention has for its object to form a gown of suitable flexible material in which the lower portion resting upon the floor will be closed and also in which the bather can have the free use of his arms when desired 20 without danger of chilling the body when the arms are used.

It has for a further object to form the arm portions of the gown so that an attendant can insert his arms therein for the purpose of 25 massaging the bather while within the gown without cooling the body by allowing the contact of the exterior air therewith.

Other objects and advantages will appear in the following description, and the novel 30 features will be particularly pointed out in the appended claims.

In the drawings, Figure 1 represents a perspective of the invention as applied in use; and Fig. 2 is a similar view of the gown, showing in dotted lines the form of the sections of 35 the gown.

Like letters of reference refer to like parts throughout both figures of the drawings.

The letter A designates the gown, which is 40 formed of a back portion A and a front portion A², joined together at their lower ends by a bottom or floor portion A³. To the lower portions of the opposite edges of these portions there are attached side portions B, provided with extended upper ends B', which 45 are not attached to the front and back portions. To the upper portions of the front and back portions a portion B² is secured, the lower edge of which is connected with the 50 arm of the gown. The outer ends of the arm portions are drawn together by any suitable means, as shown at B³—for instance, by an

elastic inserted therein. The upper portion of the front and rear portions are secured together above the arm portions by an inserted 55 piece a to form the shoulder and are provided with a draw-string A⁴ to secure and close the gown about the neck of the bather. At the lower portion of the gown a suitable inlet b is provided, through which heated air or vapor of any desired kind may be introduced 60 into the gown. The front portion A² is inclined upwardly from the bottom toward the back, so as to provide an enlarged space at the base of the gown for the reception of the 65 knees of the bather when seated in the gown.

The gown may be made of any desired material—for instance, cloth, waterproof canvas, or rubber—which material is flexible and will retain the heat or steam and exclude the 70 exterior atmosphere. The gown is formed of suitable dimensions to admit the whole body of the bather, entrance being made from the top portion, and upon the bottom or floor portion of the gown a chair or stool may be 75 placed, upon which the bather may sit.

It will be observed by this construction that the bather is completely inclosed and the heat or steam used is free to come into contact with all portions of the body, while 80 the inclined front portion provides ample room for the legs and knees of the bather and for a foot-bath, if the same is desired to be used in connection with the gown. The enlarged arm portions permit the bather to 85 thrust his hands through the sleeves, so that free use of the arms may be obtained to adjust the quantity of heat or vapor desired and also to partake of nourishment or to apply cool compresses to the head, if necessary. 90 By this form of sleeve the heat or vapor is permitted to come into contact with the arm and the body adjacent thereto, and they also permit the passage of an attendant's arm through the sleeve-opening for the purpose of 95 massaging the bather while in the gown without permitting the entrance of exterior atmosphere into the gown to chill the body. The sleeve and neck openings in the gown surround the wrists and neck, respectively, 100 so as to exclude the entrance of air and prevent the heat or vapor from escaping from the gown. The strip joining the front and rear portions of the gown at their upper ends

provides a shoulder portion *a*, which will rest upon the shoulder of the bather to retain the gown in position and prevent drawing of the same.

- 5 By forming the gown completely closed at the lower portion all escape of heat and vapor at that point is prevented, while the floor of the apartment in which the gown is used is protected against the effects of the heat or 10 vapor or condensed moisture which would result in the use of the gown and which would be liable to injure the carpet or other material upon the floor of the room in which the bath is used.
- 15 The gown has been described as composed in part of front, bottom, and rear sections; but it is obvious that these portions may be formed of a single piece of material and the side and arm portions secured thereto, as 20 hereinbefore described. It is also obvious that numerous changes may be made in the construction and configuration of the gown without departing from the essential features of this invention as defined by the appended 25 claims.

Having described our invention and set forth its merits, what we claim as new, and desire to secure by Letters Patent, is—

1. A bath-gown composed of flexible material and provided with a body portion having

side openings extending the width of the gown and downward from the shoulder portion thereof, a rear portion, a front portion of greater length than the rear portion, tapering side portions connected to the front 35 and rear portions at their lower ends and extended at their upper ends to form the lower portion of the sleeve, tapering sleeve portions to form the upper portion of said sleeves, and means for contracting the neck and outer ends of the sleeve portions; substantially as specified.

2. A bath-gown comprising front, bottom and rear portions, said front portion being of greater length than the rear, tapering side 45 portions secured to the front, bottom and rear portions at their lower ends to form side openings extending the width of the gown downward from the shoulder portion thereof, tapering sleeve portions secured to the upper 50 ends of the front, rear and side portions, and means for contracting the outer ends of said sleeve portions; substantially as specified.

In testimony whereof we affix our signatures in presence of two witnesses.
